UNITED STATES PATENT OFFICE.

THOMAS H. RHEDMON, OF MEADVILLE, PENNSYLVANIA.

ADJUSTABLE STAND.

1,393,165.

Specification of Letters Patent. Patented Oct. 11, 1921.

Application filed November 7, 1919. Serial No. 336,322.

To all whom it may concern:

Be it known that I, THOMAS H. RHEDMON, a citizen of the United States, residing at Meadville, in the county of Crawford and 5 State of Pennsylvania, have invented new and useful Improvements in Adjustable Stands, of which the following is a specification.

This invention is designed for use in re-10 pairing motors, particularly automobile motors. It is desirable to have the motor supported in such a manner that it may be swung in different positions to provide for convenience of operation and conditions of 15 light. It is also desirable to have the support so formed that it may be adjusted to different motors.

The invention is illustrated in the accom-20 panying drawings as follows:—

Figure 1 shows a plan view of the stand. Fig. 2 an end elevation. Fig. 3 a side elevation of the base. Fig. 4 a part of the swinging support. Fig. 5 a side elevation of the upper end 25 of the frame.

1 marks the base. This is formed of longitudinally arranged angle irons. A wheel 2 is journaled on each rounded end of a squared rod 2^a at one end of the base and 30 supporting lugs 3 project from the opposite end of the angle iron base 1. By this construction it is possible to move the stand in different positions relieving the weight somewhat from the lugs and yet the lugs supply 35 sufficient resistance to retain the frame in the position where it is desired to operate.

The frame has the upright standards 4 which are formed preferably of angle irons with a U-bend, one leg being preferably ver-40 tical and the other slightly at an angle so as to more thoroughly brace the upright. A cross beam 5 extends from one leg across the frame and a cross beam 6 from the other leg across the frame, the lower angle iron of the 45 cross beams 5 and 6 affording a securing means to the base 1. The cross beams 5 and 6 are secured to the legs of the upright or standard by means of bolts 7 and with the base by means of bolts 7^a. A brace 8 is se-50 cured to the beam 5 by means of bolts 8^a and has the upwardly extending ends which are secured to the leg of the brace 8 by means of bolts 8^b. A similar brace 9 is secured to the cross beam 6 by means of bolts 9^a and 55 with the upright by means of bolts 9^b. It will be seen, therefore, that the frame

formed with the base and upright standards is very rigid and yet the space between the standards is open or unobstructed so as to permit of the movement of the swinging 60 support within the space.

The upper face 10 of the standard 4 forms a support for a bearing for the swinging support. This bearing is in the form of a clamp having a base 11, a bend 12 and a 65 projection 13. A bolt 14 extends through the part of the standard 10, the plate 11, projection 13 into an elongated nut 15. A handle 16 extends through the nut 15 by means of which the bearing may be contracted or expanded as desired. The plate 11 is preferably permanently secured to the upper part 10 of the standard by means of bolts 11^a.

Trunnions 17 are arranged in the clamp-75 ing bearings and extend from the sides 18 of a swinging support. These sides are in the form of angle irons and are connected with the cross beam 19 by means of the corner irons 20. The corner irons are connected 80 with the side beams 18 and cross beam 19 by means of bolts 21. A series of holes 22 are arranged in the side beams by means of which the endwise position of the cross beam 19 may be adjusted by changing the bolts 85 21 and the cross beam 19 has a series of openings 23 by means of which the distance between the side beams may be adjusted and the cross beam secured by means of the bolts 21. The height of the cross beam rela-90 tively to the side beams may also be adjusted by utilizing the openings 20^a in the corner irons. In this instance again the bolt 21 is removed and the cross beam adjusted to the point desired. 95

It will be noted that the trunnions when the clamps are loosened not only permit of the swinging of the support but permit of the adjustment of the side beams in and out to any width desired. This gives a very 100 much more rigid support than where the entire frame is adjusted in width.

What I claim as new is:—

1. In an adjustable stand, the combination of a frame comprising side standards; 105 a swinging work support; trunnions extending from the support; and clamp bearings for the trunnions permitting rotary and axial movement of the trunnions when released whereby the support may be tilted 110 and adjusted in width.

2. In an adjustable stand, the combina-

- tion of a frame comprising standards; a swinging work support having side beams and a cross beam; an adjustable connection between said beams; trunnions extending from the side beams; and clamp bearings for the trunnions permitting rotary and axial movement of the trunnions when released whereby the support may be tilted and adjusted in width.
- 10 3. In an adjustable stand, the combination of a frame comprising side standards; a swinging work support comprising side beams and a cross beam; corner plates connecting said beams, said connections being adjustable; trunnions extending from the side beams; and clamp bearings for the trunnions permitting rotary and axial move-

ment of the trunnions when released whereby the support may be tilted and adjusted in width.

4. In an adjustable stand, the combination of a base; standards extending uprightly from the base; cross beams connecting the standards adjacent to the base; braces between the cross beams and the standards; a swinging support; clamp bearings on the standards; trunnions on the swinging support extending into the clamp bearings; and means for adjusting the width of the support, said adjustment involving axial movement of a trunnion in a bearing.

In testimony whereof I have hereunto set my hand.

THOMAS H. RHEDMON.
